UNITED STATES PATENT OFFICE.

IRA M. CLARKE, OF NEW MARTINSVILLE, WEST VIRGINIA.

DESIGN FOR A COMBINATION HOLDER FOR TOILET PREPARATIONS.

Application filed May 11, 1926. Serial No. 17,658. Term of patent 3½ years.

To all whom it may concern:

Be it known that I, IRA M. CLARKE, a citizen of the United States, residing at New Martinsville, in the county of Wetzel, State of West Virginia, have invented a new, original, and ornamental Design for Combination Holder for Toilet Preparations, of which the following is a specification, reference being had to the accompanying drawing, forming part thereof.

In the drawing the figure represents a view in side elevation of my novel design.

I claim:—

The ornamental design for a combination holder for toilet preparations, substantially as shown.

IRA M. CLARKE.
